UNITED STATES PATENT OFFICE.

JAMES W. S. PETERS, OF KANSAS CITY, MISSOURI.

DESIGN FOR A GAME-BOARD.

SPECIFICATION forming part of Design No. 35,013, dated August 27, 1901.

Application filed May 10, 1901. Serial No. 59,706. Term of patent 14 years.

To all whom it may concern:

Be it known that I, JAMES W. S. PETERS, a citizen of the United States, residing at Kansas City, in the county of Jackson and State of Missouri, have invented and produced a new and original Design for Game-Boards, of which the following is a specification, reference being had to the accompanying drawing, forming part thereof.

10 The drawing represents the playing-face of a game-board, showing my new design.

The board itself is square in form. The playing-surface occupies the center of the board and is circular, being defined by three 15 circular lines, as shown. The border or space between said circles and the edges of the board is decorated as follows: In one corner is a representation of a Chinese junk. In the opposite corner diagonally is represented a 20 similar vessel with sails set. In the other two corners are shown a mermaid holding a shell and a figure of Neptune with his trident, respectively. Behind and between these four figures is a background of seaweed or other 25 aqueous growths. Within the said circles bounding the playing-surface, at one side thereof, seven squares are arranged, as shown, each square displaying the emblem or flag device of China. Directly opposite said squares 30 and arranged symmetrically thereto are seven

squares of the same size bearing, respectively, the emblems or flag devices of seven different nations. Straight lines connect certain of said squares, as shown, and zigzag lines, not touching any of the squares, have their ends 35 terminating at the inner circle, which bounds the playing-surface. The six spaces thus formed between said lines and said inner circle may be colored, as red, to represent land, and the space within said lines—that is, the 40 central portion of the board—may be given a different color, as green, to represent water. Uniformly distributed over said central portion of the playing-surface are thirty squares, smaller than the squares bearing the flags of 45 nations, described heretofore, and having their sides arranged obliquely to the sides of the game-board, as shown.

Having now fully described my invention, what I claim as new, and desire to secure by 50 Letters Patent, is—

The design for a game-board, as herein shown and described.

In testimony whereof I affix my signature in the presence of two witnesses.

JAMES W. S. PETERS.
